J. L. Jackson's Design for a Screen.

921,929.

Patented, April 5, 1861.

Inventor

James L. Jackson

James L. Jackson, of New York, N.Y.
Letters Patent No. 1929-Dated April 6th 1864.

DES. 1924

Design for a Screen.

The schedule referred in these Letters Patent and making part of the same.

To all whom it may concern:

Be it known that L. James L. Jackson, of the City, County and State of New York, have invented a new Design for a Screen to surround a steam coil or other body; and do hereby declare that the following is a full, clear and exact description of the same, reference being had to the accompanying photograph which forms part of this specification and which is taken from such a point as to exhibit one side and one end of the screen.

The screen has a base A, and an entablature B, and the space between these is panelled in arched panels, C, C, and quadrangular panels D. Above or on the upper part of the base is a moulding a, b, composed of a bead and ogee, and below this it is plain with the exception that it has panels e, of ornamental reticulated work, the character of which is well represented in the photograph. The lower part of the entablature is formed with a cavetto as shown at c, and above it is plain with the exception that it has small oval openings d, d, the edges of which are ornamented with scroll work, and between these openings there are small circular recesses e, e.

The panels C, C, and D are almost entirely composed of open-work. Each panel has a raised ornamental border f in which are transverse oblong openings g, g, rounded at their outer ends, the said openings in the arched upper portion of the panels C, C, being radial to the centre of the arch. Within and concentric with each of the arches of the panels C, C, there is a circular series of ornamental openings g, of oblong form with rounded ends radiating from the centre of the arch, and within these a circular series of small

DES. 1929

2 circular openings i.e. In the centre of the circle there is a projecting boss in the centre of which is an open ornament h. which is well represented in the photograph, and around this ornament there is a circular series of ornamental holes j. The space within the panel, below the circular series of openings q, is filled with ornamental reticulated work similar to that of which the panels k. k. in the base are composed. Over the arches of the panels l. l. there are corner pieces l. c. of open work, the openings being of elliptical form, the partitions between them being represented by crossing ribbons. The whole of the panel within its ornamental border f is filled with open work of the same character as that in the corner pieces l. c.

The corners of the screen are formed to represent pillars H, the bases and capitals of which are ornamented to correspond with the base I and capitals B.

What I claim as my invention, and desire to secure by Letters Patent, is—

The design and configuration of the screen herein described and represented in the accompanying photograph.
